OXIDATION OF ORGANIC COMPOUNDS WITH A CHROMIC OXIDIZING AGENT

Nicholas Thomas Farinacci, New York, N. Y.

No Drawing. Application September 15, 1953,
Serial No. 380,369

12 Claims. (Cl. 260—376)

This application is a continuation in part of my copending application Serial No. 153,987, filed April 4, 1950, and now abandoned in favor hereof.

This invention relates to improvements in the oxidation of suitable organic compounds with oxidizing chromium compounds in a manner whereby the reduced forms of the oxidant are continuously removed from the reaction zone and solution as an inert solid phase in the course of the oxidation. Particularly the invention relates to a method of oxidizing selected organic compounds with oxidizing chromium compounds which is characterized by carrying out the oxidation in the presence of an agent which continuously removes substantially all of the trivalent chromic ion from the reaction zone and solution phase. More particularly the improved process relates to the oxidation of suitable organic compounds with an oxidizing chromium compound in the presence of an orthophosphate ion producing compound whereby the trivalent chromic salts are continuously and completely separated from the reaction zone and solution and thereby rendered inert and readily separable. Several advantages result from such removal which include steady oxidation potentials, economies resulting from simplified operations and lower consumption of materials. At the same time this removal generally improves operating conditions so that more complete conversions and higher yields of valuable products are obtained.

Chromic acid oxidation is frequently used in the fine chemical industry to manufacture oxygenated organic materials which are valuable intermediates for the production of hormones, dyestuffs, condiments and perfumes. Numerous procedures utilizing chromic acid have been described to degrade steroid side chains and to convert benzenoid hydrocarbons to quinones, ketones and acids.

Such processes invariably are complicated by the accumulation of large amounts of soluble chromic salts and water during reaction. The accumulation of the soluble chromic salts requires either costly operations for their removal or increased costs because excessive amounts of costly chemicals must be used in subsequent operations to offset this accumulation of the chromic salts. The accumulation of water further complicates the oxidation because it tends to increase the solubility of the chromic salts and thus further increase costs. It is common knowledge in this art that the accumulation of water and chromic salts in these processes generally retard and stop reaction resulting in low conversions and poor yields of valuable products. Attempts have been made to overcome the accumulation of water by the inclusion of sulfuric acid with the chromic acid.

It is known empirically that the inclusion of sulfuric acid with chromic acid, for example, in an acetic acid solution of steroid derivatives strongly increases the initial activity of the chromic acid oxidation. Even with moderate concentrations of sulfuric acid there is a large increase of acidic organic by-products. Thus Schwenk and Whitman in U. S. 2,244,968 found that chromic-sul-

2

furic oxidation of cholesteryl acetate dibromide increased the amount of corresponding by-product cholenic acids several times over that found where chromic acid alone was used in the usual processes. However the cholenic acids are of little value as a by-product in this industry. Similarly Bretschneider in U. S. 2,246,341 converted cholestenone to 70-80% steroid acids in his process using concentrated sulfuric acid solutions of chromic acid.

While the further disadvantages of low conversion is shown in the chromic-sulfuric oxidation of U. S. 2,244,968 by the recovery of a large amount of starting cholesterol acetate it also shows the additional disadvantage of requiring an excessively large amount of zinc dust for the later debromination step, to overcome the accumulation of chromic salts in their oxidation mixture. In such manner it is obvious that the inclusion of sulfuric acid in chromic acid oxidations increases costs of operations and losses due to excessive destruction of materials either to produce non-useful by-product acids, or overcome accumulations of chromic salts. The use of other acids such as nitric, hydrochloric and the like results in similar disadvantages.

It also is known in the hormone industry that sulfuric-chromic and nitric-chromic tend to destroy the valuable intermediates by further degrading them to steroid acids or tar thereby lowering yields. Attempts to overcome these disadvantages by working at lower temperatures result in other disadvantages of decreasing solubilities of reactants and increased power costs for cooling and mixing.

Further, the strong sulfonating action of sulfuric acid tends to restrict its general use for the oxidation of anthracenes and anthraquinones and other aromatic compounds.

It has now been found in accordance with my invention that a commercially advantageous process for the manufacture of selected valuable oxygenated organic materials is made available utilizing an oxidizing chromium compound in conjunction with a trivalent chromic ion species removing agent. As a result of this continuous removal of trivalent chromic salts it has been found that the oxidation is steadier, more selective, more complete and proceeds steadily at normal temperatures. Yields are more satisfactory and a minimum of undesirable by-products are produced when the hexavalent chromium compound oxidation is carried out in the presence of a suitable amount of an orthophosphate producing compound, for example, phosphoric acid alkali phosphates and the like which remove the chromic ion from the reaction zone as soon as it forms as an insoluble inert trivalent chromic phosphate. Further additional advantages may be obtained by the utilization of calcium acetate to reduce acidity and remove excess phosphate ion.

As a result of the removal of said trivalent chromic salts the oxidation proceeds steadily and rapidly at convenient temperatures to produce satisfactory conversions and yields of valuable products while at the same time undesirable side reactions are considerably reduced. When, for example, the process is used for the degradation of steroid side chains such as cholesteryl dibrom acetate, the major products are the corresponding dehydroisoandrosterone and pregnenolone suitable for the preparation of valuable hormones, testosterone and corpus luteum hormone. Similar advantages are gained when the process is used to prepare valuable quinones and ketones from appropriate organic raw materials such as anthraquinone from anthracene, benzophenone from diphenylmethane, and the conversion of 2-methyl anthraquinones to the corresponding 2-carboxylates. In all these oxidations with this method there is immediate and complete removal of trivalent chromium salts from the

reaction zone and removal from the mixture as solid inert insoluble phases to provide resulting large overall conversion of starting material to valuable products while the usual extensive degradation of starting materials and products is substantially avoided, because of steady but moderate oxidation potentials provided by the combination of oxidizing chromium and orthophosphate species.

It is an object of this invention to obtain high yields of valuable oxygenated organic synthetic intermediates for hormone, dyestuff, condiment, perfume and the like manufactures by the selective oxidizing chromium compound oxidation of suitable readily available low cost materials in the presence of orthophosphate producing agents which continuously remove trivalent chromic salts from the reaction zone and solution during oxidation with the oxidizing chromium compound utilized.

It is also an object of the invention to provide advantageous conditions for the oxidation of suitable organic materials by an oxidizing chromium compound by utilizing orthophosphoric producing agents for the dual purpose of supplying both an acidic function and a continuous-removal of substantially all the trivalent chromic salts from reaction zone and solution as soon as they are produced by reduction.

It is still another object of the invention to maintain particularly favorable conditions for the oxidation of suitable organic compounds by an oxidizing chromium compound and an orthophosphate producing agent and favorable to the production of valuable products, but unfavorable to further degradation of valuable products and extensive degradation of starting materials while maintaining steady moderate oxidation potentials and removing trivalent chromic salts continuously and also removing excess oxidizing chromic compounds and excess orthophosphates from the homogeneous reaction mixture.

It is still a further object of the invention to remove from the reaction mixture materials such as trivalent chromic ions, excess oxidizing chromium compound and excess orthophosphate producing compounds such as by the additional use of calcium acetate in order readily to provide separation into portions of substantially only organic constituents which require a minimum of reagents for further operations such as zinc for dehalogenation of halogenated organic products, and further readily provide more economical operations which result from the efficient removal of all inorganic components of the mixture as by simple filtration and decantation from inorganics collected in solid phases.

It is still further another object of the invention to provide hydrogen-ion buffered reaction zones by utilizing an oxidizing chromium compound in conjunction with mixtures of orthophosphoric acids and their alkali salts so that while substantially all the trivalent chromium salts are removed as an inert solid phase only moderate changes of hydrogen-ion concentration are possible due to its stabilization by the buffering action of the phosphates and thus tending to stabilize the oxidation potential which depends on chromic species and hydrogen ion concentrations. Thus there is uniquely provided buffering systems thereby which is not possible with sulfuric nitric, hydrochloric and the like compounds.

In accordance with the invention, suitably protected organic starting materials which are dissolved in a suitable inert solvent, for example, acetic acid are treated with an oxidizing chromium compound or chromyl compounds in the presence of an orthophosphate producing compound such as phosphoric acid, alkali orthophosphates or orthophosphoric anhydrides. Inert solvents such as water, acetic acid, etc., may be used to dissolve or partially dissolve the chromium and orthophosphate compounds. When reaction has proceeded to a desired degree, further treatment may be made as with calcium acetate to remove excess orthophosphate by converting to insoluble calcium orthophosphates. During oxidation

the chromic ion produced by reduction of the oxidant at once separates out as a readily filtrable insoluble trivalent chromic phosphate thus maintaining the initial substantially trivalent chromic-ion free conditions during oxidation. The oxidant may be added portionwise over the period of time during which the desired degree of reaction occurs. Excess of oxidant, if added, may be reduced by suitable addition of a reductant such as alcohol which converts the oxidizing chromium compound to trivalent chromic, which by conversion to orthophosphate salt results in the removal of substantially all of the added chromium as an insoluble trivalent chromic phosphate. Sufficient orthophosphate, for example, as phosphoric acid, alkali orthophosphates or anhydrides is added to remove all the chromium which may form and excess orthophosphate, if added may be removed as an insoluble calcium phosphate by addition of a suitable amount of calcium acetate or other calcium salts. When acetic acid is the reaction solvent excess calcium acetate also separates out as a solid phase, thus resulting in complete removal of inorganic salts.

Thus, at this stage, the new process provides portions containing substantially only organic materials including valuable oxidized intermediates and filtrable and decantable inorganic solids. When in this process a solution, for example, of halogenated organic products in acetic acid is separated because it is free of inorganics it may be directly dehalogenated with a minimum suitable amount of zinc. It is obvious that these separations effected only by employment of the new process increases the over all efficiency of oxidation compared to the gross inefficiency of all the usual chromic acid oxidations. While the usual chromic acid oxidations require costly extractions, purification of materials or disproportionate amounts of reagents such as zinc to overcome accumulations of chromic salts, the new process considerably reduces or eliminates these costs.

The simple mixture of organic products which usually is recovered in filtrate may be directly processed with minimum costs to recover its components by usual means i. e., watering out, immiscible solvent extraction, evaporation, alkali washing, semi-carbazone formation, etc.

In this specification and claims, all parts and percentages are by weight unless otherwise indicated.

In order to further illustrate and point out some of the advantages of the invention, the following examples are included. These, however, are merely illustrative and are not to be construed in any way as limitative of the invention as it is otherwise disclosed and claimed herein.

Example 1.—Steroid side chain oxidation

To a solution of 3.8 kgm. of dibromcholesteryl acetate in 138 liters of glacial acetic acid in a stirring kettle, 55 there is added portionwise at 35° C. over 1.5 hours chromic anhydride, kgm. 1.3; 85% syrup phosphoric acid, kgm. 8.2; glacial acetic, liters 2.5.

The amount of chromic phosphate triacetic precipitate is used to estimate the degree of completion. Then 0.05 kgm. of methanol is added and the mixture is slurried with 9 kgms. of calcium acetate. The solution of organic products filters free of the chromium, calcium and phosphate salts. The filtrate is treated directly with 0.4 kgm. of zinc dust at 50° C., then warmed to 70–80° C. for 2 hours. Low pressure evaporation of the acetic acid from the filtrate and benzene extraction of the solution yields 2.36 kgm. of steroid products from which 0.47 kgm. of total acids are removed by alkali extraction and 1.8 kgm. of neutral oil recovered. The neutral oil assays 0.120 kgm., 6.8% dehydroisoandrosterone and the total debrominated acids are 16% by weight of products. X-ray analysis of acids indicates a 3% yield of 3 acetoxy $\Delta^5,6$ cholenic acid compared to isolation of 12% in U. S. 75 2,244,968 using chromic-sulfuric. The expected amount

of chromic phosphate triacetic precipitate; 4.2 kgms. is found which corresponds to complete removal.

Example Ia.—Deleterious effects of sulfuric acid increased production of acidic by-products and extensive degradation

76 gms. of dibromcholesteryl acetate is dissolved in 3 liters of glacial acetic and treated with 60 gms. of chromic anhydride mixed with 175 gms. of 85% H_3PO_4 and 125 gms. of concentrated sulfuric acid. The temperature is kept at 50° C. and reaction is complete in 1.7 hours. The neutral oil recovery is 47%, while 63% of the cholesterol is converted to acids. The neutral oil assays (1.05 gm.) 2.8% dehydroisoandrosterone (of theory). This example shows the effect of sulfuric acid to lower yields of dehydroisoandrosterone (compare Example I) with the extensive degradation of cholesterol to by-product acids of little value.

Example Ib.—Deleterious effect of H_2SO_4

31 gms. of dihydrostigmasterol 5-6 dibrom acetate dissolved in 1.2 liters of acetic acid is treated with 24 gms. of CrO_3 mixed with 76 gms. of 85% H_3PO_4 and 58 gms. conc'd H_2SO_4 . The reaction is complete at 50° C. in 1.25 hours. There was a recovery of 34% neutral oil which assayed 1.3% dehydroisoandrosterone while 66% conversion of the sterol to acids indicated the property of sulfuric acid to degrade sterols to acid by-products of little value.

Example Ic.—Deleterious effects of H_2SO_4

31 gms. of dibromcholesteryl acetate in 1200 cc. glacial acetic, stirred at 50° C., is treated with 70 gms. of 85% H_3PO_4 and 50 gms. of 95% H_2SO_4 for 1.1 hours when reaction is complete. The recovery of neutral oil was 8.7 gms. (43.6%) while 56% of the cholesterol was converted to acids. The neutral oil assay is 1.5% dehydroisoandrosterone of theory. These examples utilizing sulfuric acid bring out the deleterious effects of sulfuric in chromic acid oxidations and point to destruction of valuable ketones (shown by lower yields) and extensive destruction of starting materials to form chiefly valueless by-product acids.

Example II.—Oxidation of secondary alcohol with the use of alkaline orthophosphates

To 10 gms. benzhydrol dissolved in 200 cc. glacial acetic acid there is added portionwise with stirring over one hour, 20 gms. CrO_3 mixed with 30 gms. of syrupy phosphoric (85%) acid and 15 gms. of NaH_2PO_4 . During oxidation at 30° C. the chromic phosphate-acetic solvate precipitates out and in two hours reaction is virtually complete. Five gms. of methanol is added to precipitate out any residual chromium and 65 gms. of $CrPO_4 \cdot 3CH_3COOH$ is recovered on the filter. The volume of filtrate is 300 cc. after washing the precipitate with acetic. One half of the filtrate is treated with 14.5 gms. of calcium acetate and the precipitate is filtered. The recovery of benzophenone after distillation and evaporation is 4.2 gms. The remainder on watering out yields 5.3 gms. of crude benzophenone. Crude yield is 94%.

Example III.—Aliphatic side chain oxidation

To 10 gms. of diphenylmethane in 200 cc. glacial acetic acid there is added 85 gms. of 85% syrupy phosphoric acid and portionwise over one half hour 30 gms. of dry CrO_3 . The temperature is kept at 35 to 40° for 1.5 hours, then raised to 50° C. for ten minutes. Five grams of methanol is added, the chromium is completely separated by filtration 99 gms. as a triacetic solvate of chromic phosphate. The organic products are removed by diluting the acetic acid solution to 2 liters with water and extracted with dichlorethane. On distillation of the dichlorethane solvent a residue of 9.9 gms. is obtained. The yield is 9.0

gms. of purified benzophenone, 88% yield of crude benzophenone.

Example IV.—Anthracene to quinone, using alkali orthophosphates

To 10 gms. of anthracene suspended in 200 cc. glacial acetic, there is added portionwise over one half hour, 30 gms. of CrO_3 and 60 gms. of NaH_2PO_4 dissolved in 125 cc. of water. The temperature is maintained at 30-35° C. and 100 cc. glacial acetic is added. After 1.5 hours, 5 cc. of methanol is added and the chromium salts are completely removed from the reaction mixture by filtration (44 gms. of $CrPO_4$ is found). The precipitate is washed with toluene to recover the anthraquinone. The filtrate is watered out to 4 liters, and 10.3 gms. of crude anthraquinone in toluene is recovered by filtration. On treatment with oleum, the recovery of anthraquinone was 9.2 gms. (80% yield).

Example V.—Quinone to carboxylate

To 10 gms. of 2-methyl anthraquinone 300 cc. of glacial acetic acid there is added portionwise over 2 hours, 30 gms. of CrO_3 mixed with 200 gms. of 85% syrupy phosphoric acid and oxidized over 3 hours at 60° C. After the addition of 5 cc. of methanol the chromium salts which are all (98 gm.) in the precipitate are filtered off and the solution is watered out to recover 11 gms. of crude 2-carboxy-anthraquinone. This is recovered in 95% overall yield from alcohol.

Example VI.—Conjugated unsaturation using alkali orthophosphates

19 gms. anethole are dissolved in 200 cc. glacial acetic acid and treated portionwise with stirring at 35° C. with 51 gms. of 85% syrupy phosphoric acid and 30 gms. of disodium acid phosphate. Over one half hour there is added 30 gms. CrO_3 dissolved in 40 cc. of water. The reaction is complete in 1.5 hours when the $CrPO_4 \cdot 3CH_3COOH$ recovered by filtration is 98 gms. The filtrate is watered out to 1.5 liters and extracted with dichloroethane from which the anisaldehyde is recovered as a residue on low temperature vacuum distillation. Crude yield of anisaldehyde by sodium bisulfite separation is 82%. Anisic acid crude recovery by alkali extraction of ether solution is 5%.

Example VII

15 gms. of isosafrole treated as in Example VI yields a 87% of piperonal.

Example VIII

15 gms. of acetyl-isoeugenol treated as in Example VI yields 90% of acetyl-vanillin.

Example IX.—Ring hydroxyl

5 gms. of 3-hydroxy, 5-6 dibromandrosterone-17-propionate is dissolved in 200 cc. glacial acetic acid and mixed with a slurry of 6 gms. of dry chromium trioxide and 25 gms. of 85% syrupy phosphoric acid, with stirring for 1 hour at 30° C. 19 gms. of $CrPO_4 \cdot 3CH_3COOH$ precipitate is recovered on the filtrate after treating the reaction mixture with 2 cc. of methanol. The filtrate is slurried with 20 gms. of calcium acetate filtered and directly debrominated with 8 gms. zinc dust at 50° C. for 2 hours. An 85% yield of testosterone propionate is recovered from the filtrate.

Example X.—Multiple group conversion

5 gms. of 4-isopropyl 4'-propenyl benzhydrol dissolved in 100 cc. glacial acetic acid is treated with a slurry of 18 gms. of dry CrO_3 and a 75 gms. 85% syrupy phosphoric acid with stirring for one hour at 30° C. 57 gms. $CrPO_4 \cdot 3CH_3COOH$ precipitate is recovered and the filtrate after treating the reaction mixture with 5 cc. methanol. The filtrate is slurried with 60 gms. calcium ace-

tate and the calcium orthophosphate precipitates removed by filtration. 3.2 gms. of 4-aceto 4'-carboxyl benzophenone and 0.5 gm. of 4-aceto 4'-formal benzophenone are recovered by watering out and selective extraction with ether and separation into acidic and neutral fractions.

The new process, the invention, is noted in the examples to be characterized by immediate, continuous and substantially complete removal of trivalent chromium as an inert solid phase. The insoluble trivalent chromic phosphate may be solvated, for example, with three to six molecules of acetic acid when concentrated acetic acid is used. As a result, in the invention method, characteristically, the reaction zones in the solution are substantially freed of trivalent chromium ion and therefore freed of the interference which the trivalent chromium ion or salts thereof when present in the solution are known to exert on the rate and extent of the oxidation reaction. It is probable that with reaction zones freed of trivalent chromium ion species these conditions favor a steady rate of oxidation which tends to drive the oxidation reaction to completion. This contrasts with the usual chromic acid oxidations which are known generally to decrease in rate as the trivalent chromium concentration increases and stop the reaction. In the new process due also to hydrogen ion buffering property of mixtures of phosphoric acids and salts, the hydrogen ion concentrations also tend to be stabilized which, of course, is not possible with, for example, sulfuric-chromic, nitric and hydrochloric and the like mixtures, with their salts because sulfuric acid and the like cannot form buffering systems. Substantially no tar, nor the like forms, and by-products such as those produced by sulfonation and polymerization with sulfuric acid and extensively degraded products do not form, as by the use of sulfuric, nitric hydrochloric and the like. The oxidizing chromic compound in the presence of orthophosphoric acids, because of moderate oxidation potentials does not tend to degrade carbonyls of ketones which are the valuable intermediates nor tend to degrade carboxylic acids. This contrasts with chromic-sulfuric and other acid oxidations which are known, for example, U. S. 2,246,341 to vigorously attack ketones and extensively degrade acids by vigorous attack of carboxyl groups.

The new process provides characteristically the immediate continuous and complete removal of trivalent chromic ion from the reaction zone and solution wherein said trivalent chromic ion is formed by reduction of oxidizing chromium salts by suitable organic compounds and converted by orthophosphates to solid insoluble phase. It tends to stabilize acidity due to buffering properties of mixtures of orthophosphoric acids and their salts. The oxidations generally proceed satisfactorily and steadily at normal temperatures or with moderate heating. In general the advantages which uniquely depend on and result from the orthophosphates are efficient and complete utilization of oxidizing chromium compound, stabilized vigor and steady rate of oxidation, stabilized acidity, avoidance of extensive degradation of valuable products and the efficient separation of chromium orthophosphate salts from the reaction zone and mixture.

These advantages result in economies in operation by providing mixtures readily separable by simple filtration or centrifugation and decantation to isolate the organic components and further economies by reducing the amounts of processing materials such as zinc for dehalogenation when halogenated products, for example, are produced as in the usual steroid oxidations. The increased conversions also provide economies in raw materials. These comprise the new and useful results afforded by the invention.

The new process employing an oxidant comprising an oxidizing chromium compound and an orthophosphate producing compound which may be used in conjunction

with calcium acetate is applicable generally to the selective oxidation of carbon-hydrogen bonds for which oxidants containing hexavalent chromium such as chromic trioxide, a bichromate, chromate and a chromyl compound are suitable. Some examples of substrates which are suitable: ethylenic compounds such as 1:1 diphenyl ethene; 5,6 dibrom stigmasterol acetate (side chain oxidation of double bond), anethole, isosafrole, isoeugenol; suitable primary and secondary alcohols such as benzyl alcohol, 4 isopropyl 4' propene benzyl alcohol, the 3-hydroxy steroids, hexanol, butanol and cinnamyl alcohol; suitable aldehydes such as heptanal, butyral, phenylacetaldehyde; suitable hydrocarbons such as diphenylmethane, 2-methyl anthraquinones, anthracenes and sterolic side chains which may include suitably protected coprosterols, dihydrochlosterols, phytosterols such as stigmasterol, sitosterol and the like. These organic compounds which are contemplated as suitable for the new process may be defined in terms of their chemical compositions to have hydrogen directly attached to a non carbonylated carbon atom whose bond is oxidatively attacked. Thus while the above types are suitable, such compounds as oxalic acid and carboxylic acids, ketones and tertiary alcohols such as tertiary butyl carbinols and certain unsaturated compounds having no hydrogen on the carbon forming the unsaturated bonds such as tetramethylethene are not contemplated to fall within the scope of the invention. Certain of said suitable materials such as the 4-isopropyl, 4'-propenyl benzyl alcohol and steroids because they contain polyfunctional groups of the specified type may be converted by attack simultaneously of several of the groups when treated in accordance with the method of the invention. Thus 4-isopropyl, 4'-propenyl benzyl alcohol is converted as in Example 10. Suitable compounds are those having a hydrogen containing non-carbonylated carbon atom in a group of C, H and O atoms, and said carbon atom is oxidatively attacked and converted to carbonylated derivatives.

When a solvent is used it should be inert to the oxidant. Examples of solvents that may be used are acetone, tertiary butyl carbinol and the like, and preferably acetic acid may be used.

Starting materials which have two or more groups susceptible to oxidation such as the sterols, may be protectively saturated by halogenation, etc., or acylated or halogen substituted for the hydroxyl group. Thus oxidation suitably may be confined to the carbon hydrogen bonds of the side chain or alternatively such as 3-hydroxy-17-keto-5-6 halogenated steroids (secondary alcohols may be oxidized to the 3-keto derivatives. Thus products which have the appropriate alcohol or ethylenic bond functions may be protected in known manner and the OH and double bond restored by hydrolysis and dehalogenation with zinc or other known dehalogenating agents.

While the oxidizing chromium compound may be added in the anhydrous form sufficient water or other inert solvent may be added to bring it into solution. Phosphoric compounds which supply an orthophosphate ion in the reaction system may be used, such as mono and diacid phosphates, phosphoric anhydride, metaphosphoric or pyrophosphoric acids. Orthophosphoric acid is preferred. The term phosphoric acid appearing in the claims include all these phosphoric materials.

The amount of phosphoric acid to be used is related to the amount of chromic ion formed during the oxidation reaction (by reduction of the oxidizing chromium compound) and should be at least sufficient to remove all the chromic ion as it formed. In general a ratio of one to four moles of phosphate to one of oxidizing chromium compound is preferred.

I claim:

1. In a method for the oxidation of an organic compound having a hydrogen attached to a carbon by means of a chromic oxidizing agent in an inert oxygenated or-

ganic solvent to produce a corresponding carbonylated compound, the improvement which comprises carrying out said oxidation in the presence of the orthophosphate group whereby by-produce trivalent chromium is substantially removed from the solution as formed as a solid chromium phosphate.

2. A method of claim 1, carried out at a temperature of about 30 to about 60° C.

3. A process of claim 2, wherein anthracene is oxidized to anthraquinone.

4. A process of claim 3, using chromium trioxide in aqueous acetic acid and a mixture of orthophosphate and alkaline orthophosphate.

5. A process of claim 2, wherein the hydrogen is attached to an ethylenic carbon atom, and a corresponding benzaldehyde is obtained.

6. A process of claim 5, applied to an alpha-beta unsaturated phenyl propene using chromium trioxide, acetic acid and a mixture of orthophosphoric acid and alkaline orthophosphates.

7. A process of claim 2, wherein the hydrogen is part of the methyl group in a methyl anthracene and the corresponding carboxy anthraquinone is obtained.

8. A process of claim 7, applied to a 2-methyl anthracene using chromium trioxide, glacial acetic acid and orthophosphoric acid.

9. A process of claim 2, wherein the hydrogen is attached to a tertiary carbon in a steroid molecule and the corresponding ketone is obtained.

10. A process of claim 9, applied to a dihalocholesteryl acyl ester using chromium trioxide, acetic acid and orthophosphoric anhydride followed by treating the

chromium salt-free solution of halogenated products with a calcium acetate, and dehalogenating the resulting product dissolved in acetic acid by means of zinc dust, separating the resulting dehydroisoandrosterone -3-acylates from the neutral dehalogenated products, hydrolyzing said -3-acylates and separating dehydroisoandrosterone therefrom.

11. A process of claim 2, wherein the hydrogen is attached to the methyl carbon atom of a diphenyl methyl compound and a corresponding benzophenone is obtained.

12. A process of claim 11, applied to 4-isopropyl-4'-propenyl benzhydrol, using acetic acid as the inert solvent.

UNITED STATES PATENT OFFICE
CERTIFICATE OF CORRECTION

Patent No. 2,794,813

June 4, 1957

Nicholas Thomas Farinacci

It is hereby certified that error appears in the printed specification of the above numbered patent requiring correction and that the said Letters Patent should read as corrected below.

Column 4, line 56, for "syrup phosphoris" read -- syrupy phosphoric --; column 6, lines 14 and 15, for "anthraquinone" read -- anthraquinone --; column 9, line 4, for "by-produce" read -- by-product --.

Signed and sealed this 8th day of October 1957.
